UNITED STATES PATENT OFFICE

157,247

DISPLAY CABINET

Jack Evans, Chicago, Ill., assignor to Century Display Mfg. Co. Inc., Chicago, Ill., a corporation of Illinois

Application December 22, 1948, Serial No. 150,316

Term of patent 7 years

(Cl. D80—11)

To all whom it may concern:

Be it known that I, Jack Evans, a citizen of the United States, residing at Chicago, in the county of Cook and State of Illinois, have invented a new, original and ornamental Design for a Display Cabinet, of which the following is a specification, reference being had to the accompanying drawing, forming a part thereof.

In the drawing:

Fig. 1 is a perspective view of a display cabinet showing my new design;

Fig. 2 is a front elevational view thereof; and Fig. 3 is a side elevational view thereof.

I claim:

The ornamental design for a display cabinet, substantially as shown.

JACK EVANS.
